WILLIAM P. DEPPÉ, OF BAY SHORE, NEW YORK.

CARBURETER.

1,163,223.

Specification of Letters Patent.

Patented Dec. 7, 1915.

Application filed August 4, 1914. Serial No. 854,924.

To all whom it may concern:

Be it known that I, WILLIAM P. DEPPÉ, a citizen of the United States, and resident of Bay Shore, county of Suffolk, and State of New York, have invented certain new and useful Improvements in Carbureters, of which the following is a specification.

My improvements relate to carbureters of the Stromberg type and are intended to 10 prove the action of the device and facilitate its use more particularly with lower grades of gasolene which contain a certain percentage of the heavier oils, or with kerosene or the like. With oil fuels of this character 15 evaporation does not take place readily without the assistance of heat and until sufficient heat can be applied to the spray, mixed with the air passing through the Venturi tube, the spray should not be allowed to 20 come in contact with the walls of the mixing chamber or outlet thereof, if possible. With the ordinary butterfly throttle valve the discharge from the Venturi tube is at once deflected to the walls of the mixing chamber 25 with the result that the unvaporized particles of oil at once coalesce and run back and cannot readily be vaporized. This results in a great loss of fuel and consequent decrease of efficiency, rated as miles per gallon 30 of fuel oil.

With my improved throttle valve, located directly above the Venturi tube, and adapted to open centrally, there is no obstruction to the passage of the mixture therethrough 35 centrally of the tube so that the spray being held in suspension by the speed of the stream of mixture does not have the same opportunity to contact with the side walls in passing toward the manifold or intake 40 passage of the engine. Furthermore I have preferably tapered the mixing chamber outlet approaching the throttle so as to produce, in effect, a second Venturi tube the constricted portion of which is at the centrally opening valve. This I have found makes for increased efficiency, particularly as the centrally opening valve is adapted to vary the constriction of the stream according to the 45 requirements.

For starting with kerosene and the lower 50 grades of gasolene, when the engine is cold, I have provided a small electric heating coil interposed between the throttle valve and the end of the Venturi tube against which 55 the spray from the nozzle is adapted to strike, the heat in the coil being sufficient to

vaporize the oil so that the mixture passing through the central opening of the throttle valve is sufficiently gasified to fire when the engine is turned over. After the engine has 60 been run for a few minutes the heating coil can be disconnected if desired.

My improved carbureter is particularly adapted to be used in connection with the well known Stanley mixer and Deppé va- 65 porizer, the latter being shown and described in my application Serial No. 832,209, filed April 16, 1914.

One form of my improved carbureter is shown in the accompanying drawings of 70 which—

Figure 1 is a side elevation partially in section; Fig. 2 is a top plan view, throttle about half open, Fig. 3 is a vertical section on the line 3—3 of Fig. 1, and Fig. 4 is a 75 perspective of one of the throttle valve leaves.

Referring to the drawings 1 represents the ordinary carbureter float chamber connected by means of a tube 2 with the primary nozzle 3 and an auxiliary nozzle 4 substantially as in well known Stromberg carbureter. The tube 2 traverses the primary air inlet 5 and is connected with a Venturi tube 6 which is concentric with the primary nozzle 80 3. An auxiliary air inlet 7 is connected with a lateral passage 8 leading over the auxiliary nozzle 4 into the mixing chamber 9 surrounding the upper end of the Venturi tube. The auxiliary air inlet 7 is closed by the 90 usual balanced valve 10 which is, in the present instance, provided with adjustable springs 11 and 12 arranged above and below the valve in the usual manner and adapted to regulate the amount of air admitted according to the speed of the engine or the 95 vacuum produced in the mixing chamber.

The features thus far described are substantially the regular construction of the Stromberg carbureter and the details of construction and operation thereof need not be further discussed except in coöperation with my improved throttle and heating device. Preferably the mixing chamber in my improved carbureter is slightly elongated at 13 100 and the interior thereof is tapered or constricted toward the top so that the constricted portion is substantially equal in diameter to a cross section of the cone of the Venturi tube 6 if it were extended this far. At this 105 constricted portion of the mixing chamber outlet I insert a centrally opening throttle 110

valve, preferably consisting of two segmental leaves 14 and 15 one overlapping the other and both provided with semicircular cut-away portions or circular openings 5 adapted to provide a shutter like valve the opening of which is substantially equivalent to the diameter of the constricted portion of the mixing chamber when the valve is fully opened. The constricted portion or Venturi like tubular outlet of the mixing chamber is 10 preferably circular in cross section and the side walls at diametrically opposite points, are perforated at 16 with segmental slots through which the leaves 14 and 15 of the throttle valve are adapted to be inserted. 15 The slots 16 are long enough to permit reciprocation of the valve leaves to open and close the valve as desired. The valve leaves 14 and 15 are preferably integral with disks 20 17 and 18 which are adapted to be inserted in lateral bosses 19 and 20 located on opposite sides of the mixing chamber and counter bored to receive the disks substantially as indicated in Fig. 4 of the drawing. The valve leaves 14 and 15 project through the segmental slots 16, which open into the counterbores of the bosses 19 and 20, the respective disks 17 and 18 being adapted to seal the slots 16. Each of the disks 17 and 18 is provided with an outwardly projecting central boss or pindle 21 and 22 and the disks with their respective valve leaves are adapted to be held in place, and permitted a limited circular vibratory movement, by means of 25 annular caps 23 and 24 screwed on to the respective bosses on opposite sides of the outside of the mixing chamber. Any suitable means for simultaneously moving the valve leaves in opposite directions are provided 30 preferably consisting of levers 25 connected by means of links 26 with a transversely disposed lever 27 pivoted at 28 to the under side of the auxiliary air inlet 12 substantially as illustrated in Figs. 1 and 2 of the drawings. 35 One of the levers 25 is adapted to be connected in the usual way with throttle controlling lever on the steering wheel of the automobile (not shown). Above the valve leaves 14 and 15 the tube again increases in diameter as indicated at 29 where the outlet 40 from the mixing chamber may be connected with a vaporizer or other pipe leading to the intake valves of the engine. For the purpose of connecting a carbureter to the intake pipes the usual flange 30 is provided substantially as indicated.

It will be noted that in this construction the tubular mixing chamber is concentric with primary air Venturi tube 6 which as 45 previously stated is concentric with the primary nozzle 3. The auxiliary air, coming in from the side of the Venturi tube 6, will circulate around the same and be drawn upward and mixed with primary mixture by 50 passing through the Venturi like outlet 13

of the mixing chamber, the opening of which by means of my centrally opening throttle valve will always be central of or in axial alinement with Venturi tube 6 below it. This is particularly desirable when using kerosene or the lower grades of fuel oils for, as 55 previously explained, these oils when thrown out in a spray from the nozzle should be kept from contact with the sides of the mixing chamber or the tubes leading therefrom until 60 thoroughly vaporized and mixed with the air. This I accomplish by having the throttle valve open centrally and the opening remain central of the chamber from the time it begins to open until it reaches full open- 65 ing.

When using kerosene with the ordinary carbureter it is difficult to start the engine, particularly when all of the pipes and parts are cold. For this reason I have provided 70 my carbureter with an electric heating coil 75 preferably located just above the upper end of the Venturi tube 6 and below the throttle valve leaves 14 and 15, transversely of the axis of the mixing chamber. The ends 80 of the heating coil are carried through the walls of the mixing chamber at 32 and 33 and insulated therefrom in any usual or preferred manner and the coil is adapted to be connected to a source of electricity which 85 connections (not shown) may be made in the usual manner.

With this device in place, in combination with my improved throttle valve, it will be seen that heating the coil slightly by passing 90 the current therethrough a suitable preliminary vaporizer is provided. The spray from the nozzle 3 will strike the heated coil and be partially vaporized and, mixed with the surrounding air carrying vapor and spray, will 95 pass up through the centrally opening throttle valve. During this time the mixture will have little or no opportunity of coming in contact with the side walls of the mixing chamber so that condensation thereof or 100 coalescence of the particles cannot readily take place. The mixture thus produced will be gasified to such an extent that upon passing into the engine it will readily ignite.

I have thus devised a carbureter adapted 105 to be used with either gasolene of any grade or with kerosene as desired.

Various modifications of the mechanical details of construction of the various elements of my invention may be made without 110 departing from the spirit and scope of the accompanying claims.

I claim:

1. In a carbureter the combination of a 115 Venturi tube like mixing chamber, a Venturi tube extending into the lower part and central thereof, a fuel nozzle central of said Venturi tube and a centrally opening throttle valve in the mixing chamber above said Venturi tube at the point where said Venturi 120

- like chamber is of least cross sectional area whereby said valve is adapted to produce a single unobstructed central opening for the passage of the fuel mixture.
5. 2. In a carbureter the combination of a Venturi tube like mixing chamber, a Venturi tube extending into the lower part and central thereof, a fuel nozzle central of said Venturi tube and a throttle valve in the mixing chamber above said Venturi tube at the point where said mixing chamber is of least cross-sectional area and adapted to open centrally of said chamber and tube, the diameter of the valve opening, when fully open, being less than the diameter of the mixing chamber at the end of the Venturi tube.
10. 3. In a carbureter the combination of a Venturi tube like mixing chamber, a Venturi tube extending into the lower part and central thereof, a fuel nozzle central of said Venturi tube and a throttle valve in the mixing chamber above said Venturi tube at the point where said mixing chamber is of least cross-sectional area, comprising leaves adapted to be moved outwardly from the center to cause the valve to open centrally of said chamber and tube, the full opening of the valve being less than the diameter of the chamber, below the valve, where it surrounds said Venturi tube.
15. 4. In a carbureter the combination of a Venturi tube like mixing chamber, a Venturi tube extending into the lower part and central thereof, a fuel nozzle central of said Venturi tube, a throttle valve in the mixing chamber above said Venturi tube at the point where said mixing chamber is of least cross-sectional area, comprising leaves adapted to be moved outwardly from the center to cause the valve to open centrally of said chamber and tube, the full opening of the valve being less than the diameter of the chamber, below the valve, where it surrounds said Venturi tube and means for moving said leaves simultaneously in opposite directions.
20. 5. In a carbureter the combination of a Venturi like tubular mixing chamber, a Venturi tube in the lower part and central thereof, a fuel nozzle central of said Venturi tube, an air inlet below the Venturi tube, an auxiliary air inlet adjacent to and surrounding the upper end of the Venturi tube, and a centrally opening throttle valve in the constricted portion of said Venturi like mixing chamber adapted to produce a single unobstructed central opening for the passage of the fuel mixture from both air inlets.
25. 6. In a carbureter the combination with primary and secondary fuel nozzles of primary and auxiliary air inlets, the primary inlet terminating in a Venturi tube concentric of the primary nozzle while the auxiliary air passage lies transversely of the secondary nozzle of a Venturi like tubular mixing chamber surrounding said Venturi
30. tube, and a centrally opening throttle valve across the mixing chamber at the constricted portion thereof above said Venturi tube, said valve being adapted in opening to produce a single unobstructed central opening through which both primary and auxiliary mixtures are adapted to pass and become blended.
35. 7. In a carbureter the combination with a Venturi like tubular mixing chamber, a fuel nozzle, and Venturi tube concentrically arranged and a throttle valve of an electrical heating coil between the Venturi tube and said valve in the path of spray from said nozzle, said heating coil being located within the flaring mouth of said Venturi like mixing chamber whereby the mixture is adapted to pass through a channel gradually decreasing in area toward said throttle valve.
40. 8. In a carbureter the combination with a Venturi like tubular mixing chamber, a fuel nozzle and Venturi tube concentrically arranged and a throttle valve of a transversely arranged electric heating coil between said valve and the end of said Venturi tube in the line of discharge thereof, said heating coil being located within the flaring mouth of said Venturi like mixing chamber whereby the mixture is adapted to pass through a channel gradually decreasing in area toward said throttle valve.
45. 9. In a carbureter the combination of a Venturi tube like mixing chamber, a Venturi tube and a fuel nozzle concentrically arranged in the lower part of said chamber and a centrally opening two leaved throttle valve located above said Venturi tube at the point where said Venturi tube like chamber is of least cross sectional area, each of the leaves of said valve being concavo-convex, the inner concave surface of the leaves being adapted to direct the flow of mixture toward the opening between said leaves.
50. 10. In a carbureter the combination of a Venturi tube like mixing chamber, a Venturi tube and a fuel nozzle concentrically arranged in the lower part of said chamber a centrally opening two leaved throttle valve located above said Venturi tube at the point where said Venturi tube like chamber is of least cross sectional area, a circular disk connected with each valve leaf the leaves and disks being revoluble about a common axis to open and close said valve, said leaves being concavo-convex whereby the inner concave surfaces thereof are adapted to direct the flow of mixture toward the opening between said leaves and means for turning said leaves simultaneously in opposite directions, the walls of said chamber being provided with downwardly curved pockets for the valve leaves to slide into.
55. 11. In a carbureter the combination of a Venturi tube like mixing chamber into which a fuel mixture is adapted to be projected and a centrally opening throttle valve at the con-
60. 65. 70. 75. 80. 85. 90. 95. 100. 105. 110. 115. 120. 125. 130.

- stricted portion of said chamber, said valve being adapted in opening to produce a single unobstructed opening central of said Venturi like mixing chamber.
- 5 12. In a carbureter the combination of a Venturi tube like mixing chamber into which a fuel mixture is adapted to be projected, provided with recesses in the walls thereof where said Venturi is of least cross-sectional 10 area and a centrally opening throttle valve provided with leaves adapted to recede into said recesses when the valve is opened thereby permitting smooth walls for the Venturi tube and an unobstructed passage there- 15 through.
13. In a carbureter the combination of a Venturi tube like mixing chamber into which a fuel mixture is adapted to be projected, a centrally opening throttle valve comprising 20 a pair of valve leaves and means for simultaneously moving said leaves in opposite directions to open and close said valve, said valve when open leaving a single unobstructed Venturi passage for the fuel mixture.
- 25 14. In a carbureter the combination of a Venturi tube like mixing chamber into
- which a fuel mixture is adapted to be projected, provided with lateral recesses in the walls thereof, a centrally opening throttle valve comprising a pair of valve leaves 30 adapted to recede into said recesses and means for simultaneously moving said valve leaves to open and close said valve, thereby leaving a single unobstructed smooth walled Venturi passage for the fuel mixture. 35
15. In a carbureter the combination of a Venturi tube like mixing chamber into which a fuel mixture is adapted to be projected, a throttle valve at the constricted portion of said chamber and a heating coil 40 below said valve transversely of said tube, whereby the fuel mixture is adapted to move in a uniformly converging stream from the coil to the valve when said valve is opened.
- In testimony whereof, I have hereunto 45 set my hand in the presence of two subscribing witnesses.

WILLIAM P. DEPPÉ.
